UNITED STATES PATENT OFFICE.

WILHELM OSKAR HEUBLEIN, OF FRANKFORT-ON-THE-MAIN, GERMANY.

MEDICAMENT AMPULLA.

Application filed March 12, 1925, Serial No. 14,935, and in Great Britain February 2, 1925.

This invention relates to ampullæ in which accurately closed quantities of liquid medicaments are contained and which generally comprise several compartments separated 5 from one another by easily breakable partitions so that the dry or gaseous substances may be mixed shortly before use with liquid solvents or other gases and dry substances.

If the liquid medicament has to be withdrawn 10 from such ampullæ by means of a syringe for injection, this is easy as the injection needle forms a long proboscidiform body which can be inserted down to the bottom of a long ampulla even through narrow 15 openings. If however the liquid medicament has to be withdrawn by means of a simple piston syringe as commonly used for rinsing cavities in the body an intermediate vessel is required which is often not at disposal 20 at disinfected state.

According to the invention the ampulla is provided at the end which is to be opened, prior to the use, with a tubular extension for holding and guiding hermetically 25 front end or the entire cylinder of a piston syringe. On the bottom of the ampulla which has to be broken and which merges into the tubular extension an upwardly directed breaking lever is preferably mounted 30 which is made in a shape known per se for ampullæ comprising several compartments and the free end of which lever may be imprisoned, in a manner known per se, in a narrowing of the ampulla. An arrangement, 35 which from the point of view of hygienics is especially advantageous, can be obtained if in the tubular extension of the ampulla a syringe cylinder of the simplest kind is removably located but so that it is hermetically 40 sealed, said cylinder containing a piston made for instance of wood and designed to be used only once. A device is thus obtained which is simple to make, easy to use and fulfills all requirements as regards cleanliness 45 and freedom from germs.

An embodiment of the invention is shown on the accompanying drawing, in which:

Fig. 1 shows the improved ampulla.

Fig. 2 shows how the piston syringe is 50 filled.

Fig. 3 shows the empty ampulla.

Fig. 4 shows the piston syringe filled and ready for use.

Referring to the drawing, 1 is the ampulla 55 filled with the liquid medicament. At the lower end of the ampulla 1 a tubular ex-

tension 3 is arranged, which is clearly shown in Fig. 3. The partition 4 between the tubular extension 3 and the ampulla 1 is curved upward and carries a breaking lever 5 which is imprisoned in a narrowing 6 at the upper end of the ampulla 1. In the tubular extension 3 of the ampulla 1 the piston syringe, shown in Fig. 4, is inserted so that the cylinder 7 of the syringe is accommodated in the tubular extension 3. The rounded point 8 of the piston syringe engages with the bottom 4 of the ampulla 1. When the piston syringe is inserted into the tubular extension 3 of the ampulla the piston 9 is pushed home and then a thin cover 11 for instance made from acetylcellulose which has previously been softened in a solvent, is fixed over the rear end of the tubular extension 3 and the handle 10 of the piston 9. Any other means, known per se, may evidently be used for airtightly closing the tubular extension.

The making ready of the piston syringe shown in Fig. 4 from the condition shown in Fig. 1 is carried out as follows:

The point 12 of the ampulla is broken off whereby the free end of the breaking lever 5 becomes accessible. The lever 5 is then pushed to the side whereby the hollow partition 4 is broken. The cover 11 over the handle 10 of piston 9 is cut off and by pulling back of the piston 9 the liquid medicament 2 is sucked into the cylinder 7 of the syringe. This sucking in of the liquid medicament from the ampulla into the cylinder 7 is illustrated in Fig. 2. As soon as the liquid medicament 2 has been sucked into the piston syringe this syringe is removed from the tubular extension 3 so that an empty ampulla, as shown in Fig. 3, remains and a filled syringe ready for use, shown in Fig. 4.

The airtight insertion and covering of the piston syringe into the tubular extension 3 of the ampulla may evidently be carried out in any other convenient manner.

I claim:

1. An ampulla for the easy withdrawing of a liquid medicament for piston syringes, comprising in combination with the ampulla proper, a tubular extension at the rear end of the ampulla and open at the rear end, a piston syringe accommodated in this tubular extension, and a cover of suitable mouldable and easily destructible material placed over the open end of said tubular extension.

2. An ampulla for the easy withdrawing of a liquid medicament for piston syringes,

comprising in combination with the ampulla proper, a tubular extension at the rear end of the ampulla and open at the rear end, a piston syringe accommodated in this tubular extension, a cover of suitable mouldable and easily destructible material closing said open end of said tubular extension, a narrowing between said tubular extension and said am-

pulla proper, a narrowing in the upper portion of said ampulla proper, and a breaking lever supported on said narrowing between said ampulla and said tubular extension and extending into said ampulla and into said second mentioned narrowing. 10

In testimony whereof I affix my signature.
WILHELM OSKAR HEUBLEIN.
